Primary Examiner—Robert M Spear*Assistant Examiner*—Cynthia Underwood(74) *Attorney, Agent, or Firm*—Mark Douma**CLAIM**

We claim the ornamental design for a drinking cup, as shown and described.

DESCRIPTION

FIG. 1 is a top view of a drinking cup showing our new design;

FIG. 2 is a bottom view thereof;

FIG. 3 is a side elevation view thereof, all other sides being the same;

FIG. 4 is a sectional view thereof taken along line 4—4 of FIG. 1;

FIG. 5 is a top and side perspective view thereof; and,

FIG. 6 is a bottom and side perspective view thereof.

The broken lines in FIGS. 1-4 surrounding an upward protrusion from the bottom of the inner cup and also a lower portion of the material between the two inner walls above the notch are included for the purpose of illustrating environment only and form no part of the claimed design. The oblique line surface treatment indicates that the article may be either transparent or translucent.
